UNITED STATES PATENT OFFICE.

SOLOMON J. MYERBURG, OF BALTIMORE, MARYLAND.

MACHINE FOR REMOVING BUTTONS FROM SHOES.

1,171,133.

Specification of Letters Patent.

Patented Feb. 8, 1916.

Application filed November 11, 1915. Serial No. 60,814.

To all whom it may concern:

Be it known that I, SOLOMON J. MYERBURG, a citizen of the United States, residing at Baltimore, in the State of Maryland, have 5 invented certain new and useful Improvements in Machines for Removing Buttons from Shoes, of which the following is a specification.

This invention relates to an improved 10 machine for removing from shoes the buttons that have been secured thereto by thread.

Button shoes are delivered to the retail dealer with the buttons sewed on the shoe in 15 a position that will usually suit the average foot of the size for which the particular shoe was intended. It is frequently found however that the buttons of a shoe are not exactly positioned to secure the best fit of 20 the purchaser's foot and it is deemed better to remove the buttons of the shoe and replace them in a different position that will secure the result desired. The machine of the 25 present invention therefore is intended to enable the dealer to expeditiously cut the thread and quickly remove the buttons from such shoes.

An object of this invention is to provide 30 a machine with improved means for pressing the shoe itself, while the uncut buttons are in a slotted tube attached to the machine, in order thereby to tighten the thread stitches that engage the shank of the buttons, or subject 35 that part of the thread which engages the button-shank to a certain amount of strain, whereby the cutter blade may more easily sever the thread engaging each button.

Another object of the invention is to provide 40 improved means for cutting the threads and releasing the buttons in quick succession.

The invention is illustrated in the accompanying drawing in which,

45 Figure 1, shows the machine in front elevation. Fig. 2, is a view of the same in top plan. Fig. 3, is a view on an enlarged scale of the lower end of the button-guide tube and the cutters at the side 50 thereof. Fig. 4, illustrates a cross-sectional detail through the lower end of the button-tube and tension plate, as if viewed on the line 4--4 of Fig. 1, and shows a button and attaching thread in position, 55 and Fig. 5, shows a cross section through the lower end of the button-tube and tension

plate,—the section being taken on the line 5—5 of Fig. 1.

Referring to the drawing the numeral 6, designates a metal casing, which in the present instance is of a rectangular shape and which is provided with an interior chamber 7, into which may slide a drawer or receptacle 8. This receptacle or drawer is provided with a knob for conveniently sliding the same into and out of the casing and the purpose of the drawer is to receive the buttons after they have been separated from the shoe as will presently be explained. At one side, the casing 6, is provided with an upwardly-extending guide tube 9, which has a channelway 10, therein whose lower end is in open communication with the casing, and at one side, this tube is provided with a slot 11, the upper end 12, of which is open and the lower end of which terminates near the casing. This slot 11, as clearly shown in Fig. 1, of the drawing, extends downwardly from the upper end of the tube 9, and curves inwardly as it approaches the casing, and the wall of said tube in which said slot is formed has an outer flat surface 13. At or near the lower end, the outer face of the tube carries a stationary cutter blade 14, which latter is somewhat off-set with respect to 85 said outer surface 13, as clearly shown in the sectional view in Fig. 4, and the beveled cutting edge 15, of said stationary blade is curved in a lengthwise direction so that a portion 16, of the said cutting edge, intermediate the two ends thereof, will project somewhat over the slot 11, in the tube. A movable cutter blade 17, seats close against the flat surface 13, of the tube and has its lower end pivotally secured to said tube by 95 a screw 18, which serves as a pivot, and the cutting edge 19, of this movable blade has position in a plane between the stationary blade and the flat outer surface 13, of the tube 9, as clearly shown in Fig. 4. This 100 cutting edge 19, of the movable blade also has its intermediate portion projecting somewhat over the slot 11, and both blades have their intermediate portions normally lapped. One end 20, of the movable blade 165 is free and has an inwardly-extending lug 21, that projects beneath the tube 9, and which is provided with a tapered projection 22, around which one end of a coiled spring 23, may seat. The other end of this spring 110 enters a socket 24, which is carried by a bracket 25, on the under side of the tube

9, and by means of the spring the free end of the movable cutter blade is constantly pressed in a direction to keep the blades lapped. A lug 26, is provided at one side 5 of the lug 21, so that by engaging the same with the finger, the operator may manually swing the movable blade end 20, downwardly away from the stationary blade. At the outer slotted side of the tube 9, I 10 provide a plate 27, which also has a slot 28, therein that registers with the slot 11, in the tube. This plate has its upper end 29, open and at opposite sides of the open slot-end, said plate has outwardly-flaring edges 15 30, which merge with the slot edges. The upper portion of this plate 27, is rigidly secured against the flat outer surface 13, of the tube by means of screws 31, but the lower tension portion 32, of said plate curves outwardly and away from said surface. This 20 lower end 32, is also somewhat spaced from the outer side of the cutter blades but will yield inwardly toward said blades when pressure is applied against the outer side. 25 Stop clips 33, are provided on the lower end of the plate and project over and engage lugs 34, that are provided on the lower end of the tube so that said lower end 32, of the plate may have only a limited outward 30 movement.

In the operation of severing the threads on a row of buttons attached to a shoe the operator will grasp the shoe in his hand and feed the heads of the attached buttons 35 35, into the upper open ends of the slots 11, and 28,—the button at the top of the shoe being fed into the slots first. The shoe 36, will then be rapidly drawn down on the outside of the plate 27, the heads of the buttons being on the inside of the slots and in the channelway 10. During this downward movement the tension portion 32, of the plate 27, will press the shoe outward while the heads of the buttons are held against 45 outward movement, consequently the thread 37, that passes through the shank 38, of the button will be stretched taut, as shown in Fig. 4, and while in this taut condition, the threads will be passed between the movable 50 and stationary cutter blades which will sever them in quick succession. The buttons upon being severed will drop into the channelway and roll down into the casing where they are delivered in the receptacle or 55 drawer 8. It will also be seen that during the operation of severing the thread the tension plate 32, not only draws the thread taut by pressing the shoe away from the slotted tube, but by such outward pressure 60 the plate prevents the leather of the shoe from possibly entering the slot or coming into contact with the cutter blades.

Having described my invention what I claim is,—

65 1. In a machine for removing sewed but-

tons from shoes the combination with a guide having a curved button-slot, said slot being open at one end to permit the buttons on a shoe to freely pass therein, of means extending along the slot to yieldingly press a shoe away from the slot to place the securing threads under tension; a blade having a cutting edge that extends along and in proximity to the slot, and means for yieldingly holding the blade.

75

2. In a machine for removing sewed buttons from shoes the combination with a guide having a curved button-slot, said slot being open at one end to permit the buttons on a shoe to freely pass therein, of means extending along the slot to yieldingly press a shoe away from the slot to place the securing threads under tension; a stationary cutting blade extending along the button slot, and a movable cutter blade also extending along said slot,—said stationary and movable blades being interposed between the slotted guide and the yielding pressing means.

80

85

3. In a machine for removing sewed buttons from shoes the combination with a guide having a curved button-slot, said slot being open at one end to permit the buttons on a shoe to freely pass therein; of a cutter blade secured to the guide at one side of the curved slot; a cutter blade yieldingly secured to the guide and extending along the opposite side of said slot, said cutter blades being lapped in front of the slot, and means extending along the outer side of the cutter blades for yieldingly pressing a shoe away 90 from the slot to place the securing threads under tension.

95

100

4. In a machine for removing sewed buttons from shoes the combination with a guide tube having a curved slot to receive the shanks of the buttons, of a plate extending along one side of the tube and having a slot coincident with the tube slot, said plate having a lower end thereof detached from the tube and sprung away from the tube, and a yielding cutter blade between the sprung end of the plate and the tube, said cutter blade extending along the curved slot.

105

110

5. In a machine for removing sewed buttons from shoes the combination with a button receptacle, of a guide tube extending from the receptacle and having a curved button slot therein, said tube communicating with the receptacle; a plate extending along one side of the tube and having a slot coincident with the slot in the guide tube, said plate having means for pressing a shoe away from the guide tube, and a cutter blade 120 interposed between the pressing means and the slotted side of the tube.

115

120

6. In a machine for removing sewed buttons from shoes the combination with a button receptacle, of a guide tube extending 125

130

- from the receptacle and having a curved button slot therein, said tube communicating with the receptacle; a plate extending along one side of the tube,—one end of said plate extending outwardly away from the tube slot; a stationary cutter between the latter end of the plate and the slotted tube, and a movable cutter blade also between the outwardly-extending end of the plate and the slotted tube. 5
7. In a machine for removing sewed buttons from shoes the combination with a receptacle, of a guide tube extending upwardly from the receptacle and having a slot with a curve therein; a tension plate at one side of the guide tube, and a cutter blade projecting over the curved portion of the slot, said cutter blade being interposed between the tension plate and the curved 10 portion of the slot.
8. In a machine for removing sewed buttons from shoes the combination with a receptacle, of a guide tube extending upwardly from the receptacle and having a slot with a curve therein; a tension plate at one side of the guide tube; a stationary cutter blade, and a movable cutter blade,—said blades being interposed between the tension plate and curved slot and having their cutting edges lapped. 15
9. In a machine for removing sewed buttons from shoes the combination with a receptacle, of a guide tube extending from the receptacle and having a slot therein; stop lugs on the guide tube; a spring presser plate at one side of the tube and having means to engage said stop lugs to limit the outward movement of the plate, and a cutter between the presser plate and slotted guide tube. 20
10. In a machine for removing sewed buttons from shoes the combination with a receptacle, of a guide tube extending from the receptacle and having a slot therein; stop lugs on the guide tube; a spring presser plate at one side of the tube and having means to engage said stop lugs to limit the outward movement of the plate, and a stationary and a movable cutter blade with their edges lapped and interposed between the presser plate and the slot of the guide tube. 25
11. In a machine for removing sewed buttons from shoes the combination with a receptacle, of a guide tube extending from the receptacle and having a curved slot therein; a yielding plate carried by the guide tube and springing outwardly therefrom, and a cutter blade pivotally secured to the guide tube and projecting over the slot of said tube, said cutter blade being interposed between the yielding plate and the guide tube. 30

In testimony whereof I affix my signature in the presence of two witnesses.
